SHOE

Tien Marcus, Holland, Mich., assignor to Holland
Shoe Company, Holland, Mich.

Application August 29, 1936, Serial No. 98,436

8 Claims. (Cl. 36—71)

The main objects of this invention are:

First, to provide an improved shoe characterized by reinforced arch construction.

Second, to provide a shoe which is proof against distortion due to the vertical load by means of a greatly stiffened and strengthened arch.

Third, to provide a shoe of the type described having a reinforcing saddle construction further strengthened by an appropriately conformed metal plate to laterally and vertically stiffen the arch.

Objects pertaining to details and economies of the invention will appear from the description to follow. The invention is defined in the claims.

A preferred embodiment of the invention is illustrated in the accompanying drawing, wherein:

Fig. 1 is a side elevational view of a shoe embodying my invention partially broken away and in vertical section.

Fig. 2 is a fragmentary longitudinal view partially broken away and in section on line 2—2 of Fig. 3.

Fig. 3 is an elevational view in transverse vertical section on line 3—3 of Figs. 1 and 2.

This invention relates to improvements on the shoe construction illustrated and described in my co-pending application, Serial No. 69,931, filed March 20, 1936, wherein a conformed leather saddle element is assembled with other shoe elements by means of a plurality of wooden pegs driven through the saddle elements normally of the same. The improvements referred to are for the purpose of eliminating possibility of collapse or distortion of the shoe when abnormal stresses or conditions are imposed thereon.

Referring to the drawing, the reference numeral 1 generally indicates a shoe characterized by the improved arch construction of my invention, having an outer sole 2 and an upper 3. The outer sole is shown as being formed of two plies 4 and 4' or an outer sole and welt. However, a single ply or still more plies may be employed. An insole 5 is stitched or otherwise secured to the outer sole and upper in a conventional manner and a longitudinal reinforcing plate or filler 6 may be inserted between the edges of the upper as illustrated in Fig. 3.

I provide a leather reinforcing saddle construction 7 similar to that shown and described in the above identified application consisting of a portion 8 following the contour of the shank of the shoe and extending into the heel thereof. The saddle 7 has an upwardly curved portion 9 formed to the shape of the upper at the arch

thereof on the inner side of the shoe. The saddle 7 is of a relatively stiff leather construction as described in my co-pending application and is provided for the purpose of laterally and vertically reinforcing the arch of the shoe and providing a 5 desirable arch support.

I have found that when subjected to excessive weights as when being worn by very heavy persons, the saddle 7 is not always sufficient to maintain the exact shape of the shoe and give the desired arch support and resistance to distortion. Similarly, the action of moisture from the feet of the wearer in some cases has caused the arch to become distorted under load to fail to perform its 10 function.

Accordingly, to correct the above mentioned defects, I provide a metal stiffening plate 10 corresponding in shape to the saddle 7 and inserted between the saddle 7 and the insole 5. The plate is relatively small, extending only partially across 20 portion 8 of the saddle and terminating short of the upwardly extending portion 9. However, the dimensions of the plate admit of alteration as desired. So inserted and rigidly secured between the saddle and insole by means to be hereinafter 25 described, the plate 10 adequately supports the saddle and hence the entire arch of the shoe, and effectively prevents collapse thereof under excessive load as well as due to a weakening of 30 the saddle by other agencies.

For the purpose of rigidly uniting the outer sole, insole, stiffening plate and saddle, I employ a plurality of rows of wooden pegs 11 driven through the parts noted after appropriate holes have been punched therethrough by awls or other 35 punching means. As described in my co-pending application above referred to, the pegs 11 are driven into the shoe structure in a direction normal to the outer surface of the outer sole and normal to the surfaces of the insole, plate and 40 saddle, to the end that an angular relation of the pegs relative to one another is provided. Such an angular relation effects a keystone bridging action of the pegs and shoe parts which is highly 45 effective in resisting vertical distortion. The pegs 11 are preferably of wood but may be made of any suitable material, fibrous or otherwise, and are of such a size or shape that they frictionally grip the outer sole, insole, plate and saddle tightly 50 whereby their displacement therefrom is prevented.

As indicated in Figs. 2 and 3, the punching operation preceding the insertion of the pegs 55 upsets the metal plate at the perforated openings therein, whereby an additional gripping action

with the saddle 7 is effected, thus further combating displacement of the parts.

The outer sole, insole, and upper are stitched together in the manner illustrated in my above-5 identified copending application.

I have illustrated and described my improvements in an embodiment which I have found very practical. I have not attempted to illustrate or describe other embodiments or adaptations

10 as it is believed that this disclosure will enable those skilled in the art to adapt or embody my improvements as may be desired.

Having thus described my invention, what I claim as new and desire to secure by Letters 15 Patent, is:

1. In a reinforced shoe, an outer sole and an upper stitched together, an insole having a relatively stiff leather saddle secured thereto, said saddle extending over the heel and shank and having an upwardly curved portion on one side thereof extending upwardly of the inner side of the upper, a metal stiffening plate conformed to the shape of said saddle inserted between said saddle and insole, and a plurality of parallel 20 rows of wooden pegs on either side of the shank and extending longitudinally thereof, said pegs being driven through the outer sole, insole, plate and saddle in a direction normal to the surface of the outer sole, whereby said pegs are angularly disposed relative to one another to rigidly support the instep arch.

2. In a reinforced shoe, an outer sole and an upper stitched together, an insole having a relatively stiff leather saddle secured thereto, said saddle extending over the heel and shank and having an upwardly curved portion on one side thereof extending upwardly of the inner side of the upper, a metal stiffening plate conformed to the shape of said saddle inserted beneath said saddle, and a plurality of parallel rows of wooden pegs on either side of the shank and extending longitudinally thereof, said pegs being driven through the outer sole, insole, plate and saddle in a direction normal to the surface of the outer sole, whereby said pegs are angularly disposed relative to one another to rigidly support the instep arch.

3. In a reinforced shoe, an outer sole and an upper stitched together, an insole having a relatively stiff leather saddle secured thereto, said saddle extending over the heel and shank and having an upwardly curved portion on one side thereof extending upwardly of the inner side of

the upper, a metal stiffening plate conformed to the shape of said saddle inserted beneath said saddle, and a plurality of wooden pegs driven through the outer sole, insole, plate and saddle in a direction normal to the surface of the outer sole, whereby said pegs are angularly disposed relative to one another to rigidly support the instep arch. 5

4. In a reinforced shoe, an outer sole and an upper stitched together, an insole having a relatively stiff leather saddle secured thereto, said saddle being curved to conform to the shape of the arch, a metal stiffening plate conformed to the shape of said saddle inserted beneath said saddle, and a plurality of wooden pegs driven through the outer sole, insole, plate and saddle and having binding engagement with all of them. 10

5. In a reinforced shoe, an outer sole, and an upper stitched together, a relatively stiff leather saddle secured in place within the shoe at the arch thereof, said saddle being curved to conform to the shape of the arch, a metal stiffening plate conformed to the shape of said saddle inserted beneath said saddle, and a plurality of wooden pegs driven through the outer sole, plate and saddle 15 and having binding engagement with all of them. 25

6. A shoe, comprising an outer sole, an insole, and stiffening means for said shoe, comprising a relatively rigid leather saddle having an upwardly curved lateral arch supporting portion, a similarly curved metal stiffening plate, and a plurality of wooden pegs driven through said outer sole, insole, saddle and plate in a direction normal to the surface of the outer sole. 30 35

7. A shoe, comprising an outer sole, an insole, and stiffening means for said shoe, comprising a relatively rigid fibrous saddle having an upwardly curved lateral arch supporting portion, a similarly curved metal stiffening plate, and a plurality of rigid pegs driven through said outer sole, insole, saddle and plate in a direction normal to the surface of the outer sole. 40 45

8. Stiffening means for a shoe, comprising a curved saddle conformed to the shape of the shoe arch and extending upwardly of the inner side of the shoe, a similarly conformed metal stiffening plate, and means for securing said saddle and plate together and to the sole of the shoe, comprising a plurality of wooden pegs driven through the sole, saddle and plate and having binding engagement with all of these. 50
